ICE CUBE MACHINE

Ward A. Ames, Faribault, Minn.

Application June 28, 1952, Serial No. 296,189

10 Claims. (Cl. 62—107)

This invention relates to new and useful improvements in ice cube machines and more particularly to new and useful improvements in ice cube making machines of the type adapted to progressively deposit ice in an open ended inverted cup.

With the advent of carbonated and other types of beverages on the market in increasing quantities, there has arisen a demand for a great volume of ice cubes to ice these drinks. The trade and the public has required ice cubes in ever increasing quantity. In order to meet this demand, manufacturers have endeavored to find ice cube making machines which will efficiently and speedily turn out large volumes of cubes. While several such machines are on the market, in an attempt to satisfy this demand, there has remained the problem of producing an efficient and inexpensive, trouble-free ice cube making machine which will rapidly turn out ice cubes.

It is therefore an object of this invention to provide a simple and economically efficient ice cube making machine which may be operated by unskilled people;

It is a further object of this invention to provide a new and improved ice cube making machine having a construction of maximum efficiency, economy, ease of operation and assembly;

It is a further object of this invention to provide an ice cube making machine which will provide ice cubes of exceptional clarity and quality;

It is a further object of this invention to provide an ice cube making machine wherein ice cubes are continuously built up by a coating of water supplied to a refrigerated surface from a supply tank and wherein any excess water will return to the supply tank to pre-cool said supply tank;

It is a further object of the present invention to provide an ice cube making machine wherein the receptacles for freezing the ice cubes are contained in the same unit housing as the water supply and the water is directed upwardly into the ice cube containing cups;

It is a further object of this invention to provide an ice cube making machine having inverted ice cube containing cups and a novel trouble-free means for directing a stream of water upwardly into said cups;

It is still a further object of this invention to provide an ice cube making machine having a novel apparatus for directing a flow of water upwardly into a series of inverted cups, said apparatus being unsusceptible to freezing or otherwise interrupting said flow of liquid;

It is still a further object of this invention to provide an ice cube machine having inverted cups for the formation of ice cubes therein which is of large volume capacity and forms ice cubes quickly and which is simple, durable and efficient in operation;

It is still a further object of this invention to provide an ice cube machine for manufacturing a plentiful supply of dry ice cubes;

It is a further object of this invention to provide an ice cube making machine having inverted cups for the formation of ice cubes therein, said inverted cups having

2

hollow walls through which refrigerant is flowed and having new and novel constructional features;

A still further object of this invention is the provision of an ice cube cup having a hollow wall for the circulation of refrigerant therethrough and a novel means for breaking the vacuum seal formed in such cup whereby the ice cube may be readily discharged therefrom;

Further objects reside in the details of construction of the ice cube containing cups, of the discs for directing a stream of water thereto and in the relative novel arrangement and containment of the various parts;

Other and further objects of the present invention are those inherent and apparent in the apparatus as pictured, described and claimed.

This invention will be described with reference to the drawings in which corresponding numerals refer to corresponding parts and in which:

Figure 1 is a side elevation partially in section of the present invention;

Figure 2 is a vertical section taken along the line and in the direction of the arrows 2—2 of Figure 1;

Figure 3 is a substantially horizontal section taken along the line and in the direction of the arrows 3—3 of Figure 1 and showing the positioning of the ice cube cups and the refrigerant supply thereto;

Figure 4 is an enlarged vertical sectional view on the line 4—4 of Figure 3 of two of the ice cube cups of Figure 1;

Figure 5 is a horizontal section on the line 5—5 of Figure 2 through two of the ice cube cups looking upwardly into the interior of the cup; and

Figure 6 is a fragmentary plan view of the ice cube cups and rubber shield showing the direction of flow of harvesting water between the cups.

Referring now to the drawings and particularly to Figure 1, there is shown a container for the ice cube machine generally designated 10. This container is provided with a rear wall 11, a forward bottom wall 12 and a forward top wall 13. Top front wall 13 and bottom front wall 12 are spaced apart to provide an aperture 14 therebetween. The container is provided with a floor or bottom 15, a top 16 and a pair of side walls 17 and 18, the side walls being of configuration best shown for wall 18 in Figure 1. The bottom wall 15 and the front and rear walls 11 and 12, as well as the side walls 17 and 18, are secured together to form a closed bottom to contain the water (or other liquid) W. This closed bottom may be formed by welding the walls together or by securing them with bolts and nuts and gaskets inbetween or any other well known or conventional means. It is noted that throughout this specification the term "water" is used to denote the liquid being frozen, but it is to be understood that other liquids may be frozen within the spirit and scope of this invention and are considered included in the term "water."

The side walls 17 and 18 are likewise secured to front walls 12 and 13 and to rear wall 11 as well as to top wall 16 in order to provide a substantially waterproof container. As noted in the accompanying drawings, the embodiment shown rests on bottom wall 15 although a base, pedestal or legs may be provided if desired.

Supported on side wall 18, as shown in Figure 2, is a motor 20. Motor 20 is supported thereon by a motor support 21, welded or otherwise secured thereto. The motor 20 is provided with an elongated shaft 22 positioned in bearing blocks 23 and 24 which are affixed to walls 18 and 17 respectively and a plurality of discs 25. Each of the discs 25 is provided with an integral collar 26 which is secured to shaft 22 by a set screw. It is noted that other means of securing the discs 25 to the shaft may be used if desired.

Each one of the discs 25 is centered beneath a file of

ice cube cups generally designated 30, as is shown best in Figures 1 and 2. Thus, with reference to Figure 2, there are ten ice cube cups 30 placed in rank and a disc 25 (ten discs in all) centered therebeneath in each instance.

A supporting web 31 is provided on wall 12 which serves to support a grille chute 32, the forward end of which extends through aperture 14. Grille chute 32 comprises a number of inclined rods 33 fixedly attached to a forward transverse rod 34 and to a rearward transverse rod 35. Rod 35, as may best be seen with reference to Figure 1, is affixed to rear wall 11 so that the chute 32 is supported by the junction of rod 35 to wall 11 at the rearward end and by resting on the flange or web 31 on the forward end thereof. As may be noted particularly with reference to Figure 2, the inclined rods 33 are positioned so as to provide openings therebetween so that a fan-shaped stream of water W1—W5 is directed from any one of the discs 25 and will pass therebetween. Rods 33 are also spaced sufficiently closely together so that any cube formed in cup 30 will be engaged thereby and will be guided thereover, as shown in Figure 1 wherein the cube is designated C, for the guided ejection therefrom.

Bottom front wall 12 is spaced outwardly from top front wall 13 a slight distance so that any water dripping downwardly from the edge of front wall 13 will drip into the inside of the bottom of the container and into the level of the water W.

Positioned by screws on side walls 17 and 18, as shown best in Figure 1, is a plate 37 which serves to provide additional support for grill 32 and to prevent any excess water from discs 25 being thrown outwardly through aperture 14 formed by top front wall 13 and bottom front wall 12 and side walls 17 and 18.

As is seen by reference to Figure 1, the discs 25 rotate in the direction of the arrow 40 whereupon water is engaged by the periphery 41 thereof and by virtue of the centrifugal force thrown in the direction of the lines W1—W5 of Figure 1.

The cups 30, as may best be seen with reference to Figure 3, are situated in ten ranks of five files, and are joined together throughout each rank. At one end of the first rank is provided a refrigerant inlet tube 40 and at the other end of the last rank is provided a refrigerant outlet tube 41. Joining the first and second rank is a curved conduit 42, joining the second and third rank is a curved conduit 43, joining the third and fourth rank is a curved conduit 44 and joining the fourth and fifth rank is a curved conduit 45.

These cups and conduits are usually made of copper but may be made of aluminum or steel, etc., if necessary. The cups and conduits are arranged so as to provide a continuous channel for the flow of refrigerant from inlet 40 and outlet 41. A pair of brackets 46 and 47 are positioned on walls 17 and 18 respectively to support the plurality of cups 30 and do so by engaging conduits 42 and 44, 43 and 45 respectively. Other means may be provided for supporting or securing the ice cube cups 30 in the top of the machine, if desired.

Positioned above the cups 30 is a layer of insulation 50 which serves to keep the cold in and the heat out. Top 16 serves to support the refrigeration unit generally designated 51 although it may be positioned remotely of the ice cube machine if desired.

Referring to Figure 1 particularly, it will be noted that the ranks of the cups 30, beginning with the back rank 51 and progressing to the front rank 55 are positioned on an arc substantially equivalent to the mean radius of the tangential streams of water W1—W5.

Positioned at each corner of walls 17 and 18 are jets 56A and 56B respectively. These jets are secured therein by rubber grommets 57 but may be otherwise secured if desired. These jets are positioned as shown best with reference to Figures 1, 2, 3 and 4, and serve to direct a

stream of water, as will be more fully explained herein-after.

Referring now particularly to Figures 1—4, each of the cups 30 is set in a rubber shield 58 provided with a plurality of upturned flanges 59, each upturned flange 59 serving to encircle and cooperate with one of the cups 30 for positioning the cup 30 therein. Only the edges of flanges 59 engage cups 30 and thus there is provided a space between flanges as shown in Figure 4. This serves to trap relatively dead air therebetween and to serve as a dead air space so that no ice bridges will be formed between cups. Disposed at the rear end of the sheet 58 (rightward with reference to Figure 1) is a downturned flange 60 which serves to position the sheet 58 against wall 11. It may be noted that there is an aperture 61 between the forward edge 62 of sheet 58 and wall 13. This allows water or other liquid to run thereoff and to drip from edge 61 into the water W. As shown with reference to Figures 1 and 3, the sheet 58 is maintained in position on the cup solely by frictional engagement of the flanges 59 therewith. However, if it is desired, other supporting means for the sheet 58 may be used without departing from the spirit and scope of this invention.

Referring specifically to Figures 3 and 6, it will be seen that the rubber sheet 58 has provided on the upper surface thereof a plurality of protuberances 75. These protuberances are of button-like shape and are positioned between each of the ranks and are off-set with respect to each of the apertures for cups 30 so as to be positioned diagonally between any two cups. This is for the purpose that when water is ejected from the nozzles 56A and 56B it will flow over the top of the cups and over the downward arc formed by the sheet 58 and drip from edge 62 down into the water W of the tank. As the water flows over the arc defined by sheet 58 it is guided by the protuberances 75 so as to flow between the cups in the direction of the arrows 77 and 78. Thus, it will be seen that any water emitted from the nozzles 56A and 56B will thus flow downwardly over the arc of sheet 58 and be guided by protuberances 75 between all of the cups. Thus, when it is desired to defrost the cups for the harvest of the cubes, the control valve for nozzles 56A and 56B is turned on so that relatively warm water is emitted therefrom and flowing around the exterior shell 79 of cup 30 communicates heat to the cube therein for melting the surface of the cube from the surface of inner shell 63 of cup 30. The protuberances are shown as round button-like protuberances but, with particular reference to Figure 6, a square protuberance 76 is shown which works equally well and may be substituted for any of the round protuberances. Other configurations such as ovals, etc., could also be used.

If it is desired, edge 62 of sheet 58 may be extended to contact the surface of front wall 13 of the tank and thus forming a water seal, so that water from nozzles 56A and 56B cannot flow downwardly into the water W in the tank. An escape port of any nature is then provided to carry off the water flowing from nozzles 56A and 56B and around cups 30. This may be provided equally within the spirit and scope of this invention.

Referring particularly to Figure 4, the cups 30 are of the configuration shown and are provided with an outer shell 79 and an inner shell 63. Outer shell 79 is of the cross-sectional configuration shown therein and is provided with a central depression 65 in which an aperture 66 is centered. Inner shell 63 is provided with a peripheral edge flange 67, a peripheral enlarged portion 68 and a central extension 69 having a hole 70 therein, extension 70 and hole 70 adapted for cooperation with depression 65 and hole 66 of the outer shell 79. The inner shell 63 abuts outer shell 79 by contact with the enlarged portion 68 of inner shell 63. The inner and the outer shells 63 and 79 are brazed or otherwise secured at this juncture. Extension 69 and depression 65 are also brazed together.

Each of the outer shells 79 is provided with two bulged protuberances 72 having ports 73 therein. As shown in Figure 5, each rank of cups has protuberance 72 in abutment with protuberance 72 of an adjacent cup and the ports 73 cooperate to provide a fluid channel therebetween. The protuberances 72 are brazed or otherwise secured together. While the cups 30 are preferably made of copper, they may be made of aluminum or steel if necessary.

Positioned on wall 18 is a nozzle 81 adapted to emit water into the machine 10.

In operation water is fed into the ice cube machine through nozzle 81 to the level shown by the water W in Figure 1, a level approximately half-way between the axis of the shaft 22 and the bottom edge of the peripheral disc 25. Motor 20 is started and discs 25 are rotated in the direction of the arrow 40 and the water is thrown upwardly into cups 30 in a fan-shaped stream indicated by the components W1—W5. Plate 37 serves to exclude any water from being thrown through the front aperture 14 of the machine through which the cubes are harvested, the bottom edge flange 31 of which also serves to support the grille 32. Refrigerant is supplied by the refrigeration unit 51 and is provided through inlet 40 through the ports 72 of the cups 30 and between the inner and outer shell 79 and 63 thereof through the conduits 42, 43, 44 and 45 and the various ranks of cups 51—55 as will be understood with reference to Figures 1 and 3 and thence through the outlet 41 back to the refrigeration unit. Thus, as the water from component streams W1—W5 progressively strikes ranks 51—55 respectively, there is built up on the inner shell 63 of the cups of each rank, an ice layer which gradually grows to a full cube. Any excess water from the water stream W1—W5 will fall downwardly into the water W in the container and thus pre-cool it. The position of front wall 13 being interior of front wall 12 will insure that any water adhered thereto will drip back into the container instead of outwardly thereof.

After the cubes have been formed in cups 30, the motor 20 is shut off stopping the spinning of discs 25, and a valve is thrown in refrigeration unit 51, as is well understood in the art to by-pass the expansion point thereof and provide hot gases to the cups 30 to melt the outer wall of the cube and hence severance adherence to the inner wall 63 of the cup 30. This utilization of a warm liquid or warm gas from the refrigeration unit forms no part of the invention per se and hence will not be described in greater detail. A further utilization of warm liquid to defrost may be had with reference to Patent Nos. 1,487,863, to Stewart; 2,054,074 to Field; 2,349,451 to Gilliam; or 2,117,658 to Motts.

At the same time a supply of relatively warm water is provided to flow through nozzles 56A and 56B which flows in the direction as indicated by lines 82 and 83 and arrows 77 and 78 downwardly around the outer shell 79 of cup 30, thus aiding in the instant defrosting of the periphery of the ice cubes.

The provision of the apertures 66—70 in the top of the ice cube cups 30 allows any vacuum which may be formed therein to be quickly broken and the cubes will drop from the cups 30 down onto the grille 32 and slide therealong as shown in Figure 1 for cubes C.

The motor 20 is then re-energized to start the flow of water from discs 25 to the cups 30. Simultaneously therewith, nozzles 56A and 56B are shut off and no more water is emitted therefrom, and the flow of refrigerant is once more started through inlet 40, cups 30 and outlet 41, and the cycle is repeated.

The upward spray W1—W5 of water from the discs 25 aerates the water and insures that the ice cubes are made progressively downwardly and consequently extremely clear. When they are harvested as described previously, the action of gravity carries them down onto grille 32 from whence they pass through aperture 14 and may be

collected in a container of any sort desired. As the cubes progress downward along grille 32 and as the spray W1—W5 has been stopped, the moisture on the surface of the cubes evaporates and the cubes are relatively dry when collected in the receptacle. Consequently, they do not tend to stick together, which is a desirable feature.

The provision of the unique ice cube forming cup 30 with the inner and outer shells 79 and 63 and cooperating depressions and extensions 65 and 69 as well as the cooperating flange 68 provides a cup which assures ease and inexpensiveness of manufacturing and the depressions 65 and extensions 69 provide a convenient way of insuring that the inner and outer walls are positioned in cooperating position. The provisions of the protuberances 72 and ports 73 allow the plurality of cups to be positioned in sequence for the flow of refrigerant therethrough and allows the ready replacement of any individual cup should it become damaged or faulty. Furthermore, the configuration of the inner and outer shells provides extreme ease of ice cube manufacture and harvesting.

If desired, the starting and stopping of motor 20 may be accomplished automatically by a timer as may be the sequence of water ejection from nozzles 56A and 56B and of refrigerant flow through the conduits and cups; or thermostatic means may be used either with or without a timer in conjunction for determining the rate of flow of refrigerant through the cups and consequently the freezing time.

The water flowing from nozzles 56A and 56B serves to meter an excess of water W in the bottom of the tank and the level of water W may vary from the level shown in Figure 1. However, it is desirable in operation that the water be kept somewhat close to this level for maximum efficiency. An overflow valve may be provided if desired to keep the water level constant.

As many widely differing embodiments of this invention may be made without departing from the spirit and scope of this invention, it is to be understood that I do not limit myself to the specific embodiments disclosed herein.

What I claim is:

1. An ice cube machine comprising in combination a tank having a front wall provided with an aperture therein and a rear wall for retaining a supply of liquid at the bottom thereof, a plurality of discs having portions rotatable progressively into and out of contact with said liquid, a plurality of inverted cups centered above each of said discs and positioned thereover for receiving liquid tangentially thrown from said disc, said cups each comprising an inner and outer shell and being connected together for the flow of refrigerant between said inner and outer shell, refrigeration means for causing a flow of refrigerant to flow through said inner and outer shells, means between said discs and said cups for receiving ice cubes which are ejected from said cups, said means being inclined from said rear wall to said front wall to guide ice cubes thereout, and said front wall above said aperture being parallel to but spaced towards said rear wall from said front wall below said aperture.

2. In an ice making machine having means for directing liquid into an inverted receptacle, means for refrigerating said receptacle for the freezing of said liquid, said inverted receptacle constituting a double walled cup having a chamber around the periphery thereof, a horizontal inlet and outlet for conducting refrigerant therethrough, said outer wall being provided with a depression on the closed end of said cup and said inner wall being provided with an extension on the closed end of said cup, said extensions and depressions abutting one another and an aperture provided therethrough.

3. In an ice cube machine comprising in combination a tank having a front wall provided with an aperture therein, and a rear wall for retaining a supply of liquid at the bottom thereof, a plurality of inverted receptacles

each having a wall to which refrigerant may be supplied, means for supplying refrigerant to said walls and rotating means for directing a stream of water into said receptacle, the improvement comprising means positioned between said receptacles and said rotating means for directing a stream of water thereto, said means being inclined from said rear wall to said front wall to guide ice cubes out of the machine, said front wall above said aperture being parallel to but spaced toward said rear wall a distance from said front wall below said aperture, and baffle means precluding the spraying of water through said aperture.

4. The apparatus of claim 3 further characterized in that said incline means comprises a grille chute.

5. An ice cube machine comprising in combination a plurality of inverted receptacles each having a wall to which refrigerant may be supplied, means for supplying refrigerant to said walls and rotating means for directing a stream of water into said receptacles, the improvement comprising a planar sheet of resilient material having apertures in which said plurality of inverted receptacles are positioned, and jet means positioned above said planar sheet for directing fluid over said planar sheet and said inverted receptacles.

6. An ice cube machine comprising in combination a plurality of inverted receptacles, each having a wall to which refrigerant may be supplied, means for supplying refrigerant to said walls and means for directing a stream of water into said receptacles, the improvement comprising an arcuately curved planar sheet of resilient material having one elevated edge and having apertures in which said plurality of inverted receptacles are positioned, jet means positioned above said planar sheet and adjacent said elevated edge for directing fluid over said planar sheet and said inverted receptacles.

7. An ice cube machine comprising in combination a plurality of inverted receptacles, each having a wall to which refrigerant may be supplied, means for supplying refrigerant to said walls and means for directing a stream

of water into said receptacles, the improvement comprising a planar sheet of resilient material having apertures in which said plurality of inverted receptacles are positioned, jet means positioned above said planar sheet for directing fluid over said planar sheet and said inverted receptacles and said planar sheet being provided with a plurality of projections between said receptacles for directing fluid emitted by said jet means against such receptacles.

10 8. The apparatus of claim 6 further characterized in that said ice cube machine comprises a four-walled compartment and said planar sheet being positioned in abutment with three of said four walls and spaced from said fourth wall.

15 9. In an ice making machine comprising an inverted receptacle means having a wall to which refrigerant may be supplied, means for supplying refrigerant to said wall and means for directing a stream of water into said receptacle, the improvement comprising said receptacle comprising a cup having an inner and an outer shell and being connected together for the flow of refrigerant between said inner and outer shell, said outer shell having a depression at its closed end and said inner shell having an extension at its closed end cooperating with said de-

25 pression and cooperating apertures provided therethrough.

10 10. The apparatus of claim 9 further characterized by the wall of said inner shell adjacent the open mouth of said cup abutting the wall of said outer shell.
